[57] CLAIM

The ornamental design for a sport utility vehicle top, as shown and described.

DESCRIPTION

FIG. 1 is a left side elevation view, the right side elevation being a mirror image thereof;

FIG. 2 is a left side elevation view with the removable top portion and the removable doors removed for clarity, the right side elevation being a mirror image thereof;

FIG. 3 is a rear elevation view;

FIG. 4 is a front elevation view with the removable top portion and the removable doors removed for clarity, the right side elevation being a mirror image thereof;

FIG. 5 is a front elevation view;

FIG. 6 is a bottom plan view; and,

FIG. 7 is a top plan view.

The broken line showing of a sport utility vehicle is for illustrative purposes only and forms no part of the claimed design. Those portions of the sport utility top not visible in the drawings form no part of the claimed design.
